UNITED STATES PATENT OFFICE.

JACOB KAUFFMAN, OF TOLEDO, OHIO.

SHAFT-LOOP.

SPECIFICATION forming part of Letters Patent No. 392,612, dated November 13, 1888.

Application filed August 9, 1888. Serial No. 281,809. (No model.)

To all whom it may concern:

Be it known that I, JACOB KAUFFMAN, a citizen of the United States, residing at Toledo, in the county of Lucas and State of Ohio, have invented certain new and useful Improvements in Shaft-Loops, of which the following is a specification, reference being had thereto to the accompanying drawings.

This invention relates to a new and useful improvement in shaft-loops; and the invention consists in the construction, arrangement, and combination of the different parts, whereby a new article of manufacture is obtained which embodies strength, convenience, and simplicity in operation.

In the drawings which accompany this specification, Figure 1 is a perspective view of my improved shaft-loop. Fig. 2 is a vertical central cross-section thereof, showing it attached to the saddle and open to receive the shaft.

A is a metallic strap provided at its upper end with a loop, B, by means of which it is suspended by a leather strap, C, from the saddle.

D is a U-shaped shaft-bearing formed integral with the strap A at the lower end thereof and projecting laterally therefrom.

E is gate secured by means of a hinge-joint, F, to the free end of the U-shaped shaft-bearing and adapted to close or disclose the throat of the U-shaped shaft-bearing.

G is a shoulder upon which the free end of the gate is adapted to rest in its closed position.

H is a spring secured at one end to the strap A in any suitable manner and projecting with its free end in proximity to the shoulder G, and adapted to lock the gate E in its closed position. The free end of the spring is provided with a lug or pin, I, engaging into a recess, J, of the strap A.

K is a loop formed at the lower end of the shaft-bearing for the attachment of a suitable strap to secure the lower end of the device to the saddle, and L is a covering of leather or fabric on the shaft-bearing.

It will be seen that by depressing the spring H the gate E can be readily thrown open, when it will fall out of the way, while the closing is effected by merely turning the latch into its

closed position, which allows the spring to automatically lock the gate in place and prevents any accidental disengagement even under heavy strain, as the lock I prevents the straining of the spring if an upward pressure is brought upon the gate accidentally.

In practice, the parts being arranged and constructed substantially as shown and described and secured to the harness-saddle at the usual height for supporting the shafts, it will be found that the device forms a very convenient shaft-loop, as it is easy for one man to guide the shafts in and out of the loops in hitching up the horse. By throwing the gates E open the shafts can drop vertically into the shaft-bearing, and thus the letting up or down of the shafts engages or disengages them from the shaft-loops.

It is a common experience that with ordinary shaft-loops, in which the engagement with the shafts has to be secured by a longitudinal engagement or disengagement with the shafts, difficulty is often encountered with some horses in hitching and unhitching, which is obviated in my construction, which permits me to hitch or unhitch the horse from the vehicle without moving the same from its position.

I preferably construct my device of malleable iron; but for more stylish harnesses I make it japanned, nickel-plated, or otherwise more ornamental.

What I claim as my invention is—

As an improved article of manufacture, a shaft-loop consisting of the strap A, provided at one end with a loop, B, and at the other end with a U-shaped shaft-bearing, D, said strap being formed with shoulder G and hole J above said shoulder, the gate E, hinged to the free end of said shaft-bearing, and the locking-spring H, secured at one end to said strap and at the other end provided with a lateral pin, I, engaging said hole J in the strap, substantially as and for the purpose specified.

In testimony whereof I affix my signature, in presence of two witnesses, this 28th day of June, 1888.

JACOB KAUFFMAN.
